WRAP-AROUND GARMENT

Ada Quinn, Ogden, Utah

Application October 10, 1941, Serial No. 414,543

10 Claims. (Cl. 2—74)

This invention relates to improvements in garments for women's personal wear, and more particularly to clothing of the wrap-around or Hoover type which may be used either as dresses or as slip-over garments to protect underneath dresses.

The principal object of the present invention is to provide a garment of this character, capable of being put on and removed with facility and presenting a neat and attractive appearance, which embodies a novel form of skirt construction ensuring adequate coverage for the person of the wearer in any position which she may assume when working about the house.

Another object is to provide an improved construction for the underlapping portion of the skirt of a Hoover type garment which holds said portion in proper position on the body of the wearer to prevent exposure even when the wearer stoops, kneels or sits down.

A further object is the provision of a new skirt structure for a wrap-around garment wherein a good fit and proper concealment for the limbs of the wearer are obtained with substantially less yardage of material than would be required for like results in similar garments of known design.

In order to attain these and other objects which will appear more fully from the following detailed disclosure, the garment of the present invention is so constructed that the skirt portion thereof is formed with a pair of lapping sections of different sizes which, when adjusted to the body of the wearer, fold one over the other in such a manner that, while the overlapping section covers substantially the entire width of the body from hip to hip, the underlapping section may be substantially narrower than the latter, in some cases extending only to or slightly beyond the center line of the garment. The upper or waist portion of the garment, to which the skirt is sewn at the waistline either with or without a belt or yoke, may open from the neck to the waistline in any suitable manner, and may be provided either with a pair of tie members or strings attached to the free edges thereof adjacent the waistline, or with buttons and buttonholes, for securing the garment in place upon the body of the wearer. When tie strings are used, the string connected to that portion of the waist to which the underlapping skirt section is secured is adapted to pass around in front of the body, beneath the overlapping section, and then out through a hole or other opening located in or near the under-arm seam, while the string associated with the overlapping section passes around the body on the outside of the garment to the center of the back.

where both of the strings may be secured together in a bow or any other desired manner.

In order to prevent the relatively narrow underlapping skirt section from dropping or falling away from the front of the body when the wearer stoops, kneels or sits, it is provided with an adjusting element or section, substantially triangular in shape when the garment is in completed form, which is secured along one side to the free edge of said skirt section, with its apex down and its base forming a continuation of the upper or waistline edge of the skirt. If desired, the adjusting element may also be made in the form of a strap secured at its lower end to the free edge of the underlapping skirt section at a point intermediate the length thereof and at its upper end to the waist portion of the garment at a point spaced from the top corner of the skirt. With either of these constructions, the adjusting element acts as a tension member which applies a diagonally directed force to the edge of the underlapping skirt section which is effective to hold the latter in its proper forward position, even when the wearer bends over.

Although it will be obvious that the novel aspects of the present invention may be embodied in garments of various styles, designs and sizes, there are shown in the accompanying drawings and hereinafter described three complete dresses and four specifically different constructions of the underlapping skirt and adjusting sections embodying the inventive concept. In these drawings, which are intended for purposes of illustration only, and wherein like reference characters indicate like parts throughout the several views:

Fig. 1 is a perspective view of one form of Hoover type dress embodying the present invention as it would appear when being worn;

Fig. 2 is another perspective view of the garment of Fig. 1, but with the tie members undone and the overlapping portions of the dress extended outward so as to better illustrate the construction of the underlapping skirt and adjusting sections;

Fig. 3 is a view showing the pattern or shapes of two pieces of material from which the underlapping skirt and adjusting sections of Figs. 1 and 2 may be made, and indicating in broken lines the additional material that would be required in a wrap-around dress of conventional design;

Fig. 4 is a view showing the two sections of Fig. 3 as they appear after being sewn together, but prior to assembly with the other parts of the dress;

Figs. 5 and 6 are views similar to Figs. 3 and 4 of a modified construction embodying an adjusting section of different shape;

Fig. 7 is a perspective view similar to Fig. 2 of another form of garment embodying the invention, having a somewhat wider underlapping skirt section and an adjusting element of the strap type, and employing buttons instead of tie members for fastening the garment in wearing position upon the body of the wearer;

Fig. 8 is a view similar to Figs. 3 and 5 showing the pattern of the underlapping skirt section and adjusting strap of Fig. 7;

Fig. 9 is a perspective view similar to Figs. 2 and 7 of still another embodiment of the invention, this garment having a relatively narrow underlapping skirt section and tie members like that of Fig. 2, but combined with a strap type adjusting element; and

Fig. 10 is a view similar to Figs. 3, 5 and 8 showing the pattern of the underlapping skirt section and adjusting strap of Fig. 9.

Referring first to Figs. 1 and 2, the garment shown therein is a Hoover type dress having an upper portion or waist comprising a back section 11, a pair of front sections 12 and 13 and short sleeves 14, and a lower portion or skirt comprising a rear section 15, an underlapping front section 16 and an overlapping front section 17.

In this embodiment of the invention, the waist portion of the dress opens down the front from the neck to the waistline, the section 12 being adapted to overlap slightly the section 13 and to be fastened thereto in any suitable manner, as by means of a button 18 positioned adjacent the neck. The waist section 12 is also provided with a sash-like piece or yoke portion 19 which extends across the entire front of the dress at the waistline, and to the lower edge of which is sewn the overlapping skirt section 17, the latter also being of sufficient width to extend from hip to hip. Secured to the free edges of yoke portion 19 and underlapping waist section 13 are a pair of tie members or strings 20 and 21, respectively, which are adapted to encircle the body of the wearer and to be adjustably secured together in the center of the back by a bow or knot 22, or in any other desired manner. Inasmuch as the tie member 21 is secured to a portion of the waist which is overlapped by the yoke portion 19 when the dress is dooned, a suitable opening 23 is provided, preferably in the seam between the back section 11 and front section 12 of the waist, through which the end of said tie member may be passed in order to meet with the tie member 20 at the back of the garment.

Although the button 18 and tie members 20 and 21 are adequate to retain the garment in proper position when the wearer stands erect, the appearance of the dress may be enhanced and the overlapping skirt section 17 more positively and neatly held in place by providing a button 24 at the waistline, adjacent the under-arm seam between the back section 11 and front section 13 of the waist, to which the end of the yoke portion 19 may be fastened, and one or more additional buttons 25 sewn to the rear section 15 of the skirt, adjacent the side or hip seam between the latter and the underlapping front section 16, for engagement by buttonholes formed in the free edge of overlapping skirt section 17.

The underlapping skirt section 16, which is sewn to the bottom edge of waist section 13 at the waistline, differs from the corresponding por-

tions of garments of the wrap-around type hitherto known in that it covers substantially less than half of the frontal area of the skirt, instead of being approximately the same size as the overlapping skirt section 17, and is provided with an auxiliary or supplementary adjusting section 26 which is of such character and is so connected to both the underlapping skirt section and the waist section 13 that, in spite of the relatively narrow width of the underlapping skirt section, the latter remains in proper position to prevent undue exposure of the wearer's person regardless of the posture assumed by the wearer.

An adjusting section of the type shown in Figs. 1 and 2 may be formed and connected to the underlapping skirt section in various ways, two examples of which have been illustrated in Figs. 3-6 of the accompanying drawings.

In the embodiment of Figs. 3 and 4, the adjusting section 26 is approximately trapezoidal in shape prior to its assembly with the underlapping skirt section 16, and may advantageously be cut out of the same piece of material as the latter in such a manner that the upper edge 27 of the adjusting section constitutes a prolongation of the upper edge 28 of the skirt section (both of these edges being curved since they are intended to be sewn to the lower edge of the waist section 13 to form the waistline seam), and the shorter of the two side edges of the adjusting section, indicated at 29, is colinear with the upper portion of the free edge 30 of the skirt section. The edge 30 is preferably straight throughout its length, although, if desired, it may be curved similarly to the opposite edge 31 which is adapted to be sewn to one of the longitudinal side edges of the rear skirt section 15. The other side edge 32 of the adjusting section is also preferably straight, diverges slightly from the opposite edge 29, and is of a length slightly more than half that of the free edge 30 of the underlapping skirt section. For best results, it is preferable that the side edge 32 of the adjusting section be cut straight with respect to the texture of the material, rather than on the bias. The fourth edge 33 of the adjusting section is cut at an angle to edges 29 and 32, and is either straight or curved, corresponding to the character of the edge 30 of the skirt section to which it is adapted to be joined when the adjusting and skirt sections are sewn together in the manner indicated in Fig. 4.

After the underlapping skirt section 16 and adjusting section 26 have been cut out in the flat in the patterns shown in Fig. 3, they are secured together by first sewing the edge 29 of the adjusting section to the upper portion of the edge 30 of the skirt section, and then moving the edge 33 over into coincidence with, and sewing it to, the edge 30. In joining the edges 33 and 30, top edge 27 of the adjusting section is pulled downwardly, as indicated in Fig. 4, so that it is no longer a direct prolongation of the edge 28 of the skirt section 16. However, when the edges 27 and 28 are then united with the regular bottom or waistline edge of waist section 13, the edge 27 is again elevated until it becomes an arcuate prolongation of the edge 28, at which time, because of the connection between the edges 33 and 30, the bottom portion of the free edge 30 of the skirt section is automatically brought forward and upward toward the center line of the dress.

The angularity between the edges 33 and 30 before they are joined, or the width of the inverted dart which is taken out between these

two edges when the adjusting and underlapping skirt sections are cut out of the same piece of material in the manner suggested by Fig. 3, may be varied in accordance with the extent to which it is desired that the lower end of the free edge 30 of the skirt section should be pulled toward the center line of the garment out of what would otherwise be its normal, straight hanging position. The length of the adjusting section is also variable, although the most satisfactory results are attained when the adjusting section extends to a point below the middle of the free edge 30 of the underlapping skirt section.

When the dress is then donned by the wearer, and properly adjusted and secured in wearing position by means of the tie members 20 and 21 and the buttons 18, 24 and 25, in the manner illustrated in Fig. 1, the adjusting section 26 acts as a sort of tension member interposed between the bottom edge of the waist section 13 and the free edge 30 of the underlapping skirt section 16, exerting a diagonally directed force upon the latter which serves to hold it in the desired forward position and to prevent its falling backwardly as the wearer moves about and assumes various postures which would otherwise tend to cause the skirt to drop open.

The construction illustrated in Figs. 5 and 6 embodies an underlapping skirt section 16 of the same shape and size as that shown in Figs. 3 and 4, but differs from the showing of the latter in that the adjusting section 26' is generally triangular in shape, rather than quadrilateral, the inclined edge 33' extending all the way to the upper edge 27' and making a smaller angle with the edge 30 of skirt section 16 than in the previous embodiment. The edge 32' of the adjusting section 26' is again preferably cut straight of the goods, but is somewhat longer than the corresponding edge 32 of the section shown in Figs. 3 and 4, with the result that, when the adjusting section 26' and skirt section 16 are sewn together as indicated in Fig. 6, the adjusting forces are exerted along a greater portion of the length of the edge 30 of the skirt section than is the case with the first construction. Forming the adjusting section in the manner illustrated in Figs. 5 and 6 thus results in a slightly smoother setting garment than is produced with an adjusting section of the character shown in Figs. 3 and 4.

Referring now to Fig. 7, the garment illustrated therein differs from that of Figs. 1 and 2 both in the construction of the underlapping skirt section and adjusting element and in the means for securing the dress in wearing position; the waist portion of the dress is also specifically different from that of the first embodiment.

As shown, the waist comprises a back section 34, a pair of lapping front sections 35 and 36 each of which has a diagonal edge extending substantially to the opposite under-arm seam when the garment is donned, short sleeves 37 and a collar 38. The three waist sections are also provided with belt portions 39, 40 and 41, respectively, to which in turn are sewn the rear section 42, front overlapping section 43 and front underlapping section 44 of the skirt. In order to secure the garment in wearing position upon the body of the wearer, the belt portion 41 is provided with a buttonhole 45 and button 46 adjacent its free end, and another button 47 adjacent its opposite end, which buttonhole and buttons are adapted to cooperate with a button 48 and buttonholes 49 and 50, respectively, associated

with the belt portion 40. The underlapping waist section 36 may also be provided with a button 51 adjacent the lower end of the collar 38 for cooperation with a buttonhole 52 formed in the overlapping waist section 35, so as to keep the garment closed at the neck.

As in the case of the garment of Figs. 1 and 2, the overlapping skirt section 43 is of sufficient width to extend from hip to hip. The underlapping skirt section 44, while somewhat wider than the corresponding section 16 of the previously described embodiment, is still of substantially less width than the overlapping section 43, so that its upper edge 53, which is sewn to the belt section 41, terminates short of the free end of the latter, and its free side edge 54 lies beneath the overlapping section intermediate the side edges of the latter when the garment is worn.

Instead of sewing a solid piece of material to the free edge 54 of the underlapping skirt section 44 and to the bottom edge of belt section 41 beyond the end of upper edge 53, similarly to the previously described structures, the adjusting element of this embodiment of the invention is formed as a strap 55 secured at its upper edge to belt section 41 adjacent the free end thereof, extending diagonally downwardly obliquely to the free edge 54 of the underlapping skirt section 44, and secured at its lower edge to said free edge at a point approximately halfway down the length of the latter. A strap of this character, particularly if cut straight of the material, constitutes an effective tension member which prevents the underlapping skirt section from dropping away from the body of the wearer as she bends over or moves to other positions wherein the skirt would tend to fall open.

In Fig. 9 there is shown still another garment embodying the invention which is similar to that of Figs. 1 and 2 in that the underlapping skirt section is relatively quite narrow, covering only about half the frontal area of the body, and tie members are employed for securing the garment in wearing position, but differs therefrom in that the adjusting element is of the strap type similar to that shown in Fig. 7.

In the form illustrated, the waist portion of the garment comprises a back section 56, a pair of front sections 57 and 58, and short sleeves 59, while the skirt portion comprises a rear section 60, a front overlapping section 61 and a front underlapping section 62. The front waist section 57 is adapted to slightly overlap waist section 58 and to be fastened thereto in any suitable manner, as by means of a button 63 and buttonhole 64 positioned adjacent the square-cut neckline. The front waist section 57 is also provided with a belt or yoke portion 65 which extends across the entire front of the dress at the waistline, and to the lower edge of which is sewn the overlapping skirt section 61, the latter also being of sufficient width to extend from hip to hip. Secured to the free edges of belt portion 65 and underlapping waist section 58 are a pair 66 of tie members 66 and 67, respectively, which are adapted to encircle the body of the wearer and to be adjustably secured together in the center of the back by a bow or knot, or in any other desired manner. Inasmuch as the tie member 67 is secured to a portion of the waist which is overlapped by the belt portion 65 when the dress is donned, a suitable opening 68 is provided, preferably in the seam between the back section 56 and front section 57 of the waist, through which the end of said tie member may be passed in or-

der to meet with the tie member 68 at the back of the garment.

The underlapping skirt section 62 is sewn at its upper edge 68 to the bottom edge of waist section 58 at the waistline, but, being only about half as wide as the overlapping section 61, terminates short of the free edge of waist section 58 so that its own free edge 70 lies beneath the overlapping section adjacent the center line of the body when the garment is worn. With a garment of this construction, it has been found that the underlapping skirt section may be held in its proper position, in spite of its relatively narrow width, by means of an adjusting element in the form of a strap 71 secured at its upper edge to tie member 67 (which, in effect, constitutes a prolongation of the bottom part of underlapping waist section 58) and at its lower edge to the free edge 70 of the underlapping skirt section 62 at a point about one-third of the way down the length of the latter. For most effective results, it is preferable that the strap 71 be cut straight of the material.

It should be apparent from the foregoing disclosure that the present invention provides a new and improved construction for the skirts of garments or dresses of the wrap-around type which not only insures that the skirt will remain closed and adequately cover the person of the wearer at all times, but also attains this result with substantially less material than is required for the skirt of wrap-around garments of known construction. In this latter connection, it will be seen from Figs. 3, 5, 8 and 10 that the total yardage of piece goods required for the adjusting and underlapping skirt sections of the present invention is materially less than that which would be used for an underlapping skirt section of conventional design.

Although three specific forms of dress and four different examples of the adjusting section construction have been described and shown in the accompanying drawings, it will be obvious that the invention is not limited to these particular structures, but is capable of a variety of mechanical embodiments. For example, while it is preferred to cut the adjusting element as a separate part of the garment and then sew it to the underlapping skirt section in the manner hereinbefore described, these two parts may also be cut in one piece with one another (particularly when the adjusting element is of quadrilateral shape like that illustrated in Fig. 3) without in any way detracting from the effectiveness of the finished construction. In fact, the entire garment may be made in one piece, if desired. It will also be recognized that garments embodying the invention may be made of any suitable materials, and are capable of innumerable variations in style and shape of both the waist and the skirt portions thereof. In the latter connection, it is obvious that the belt and yoke portions associated with the waists of the various embodiments illustrated can be omitted, if desired, and the skirt sections and tie members (or buttons, where used) sewn directly to the waist sections. Accordingly, the terms "waist portion" and "waist section" appearing in the appended claims will be understood to include the belt or yoke portions when the latter are used, as well as those portions of tie members which function as belt or yoke portions, like the inner end of tie member 67 in the garment of Fig. 9 to which the adjusting strap is secured.

Various other changes, which will now suggest themselves to those skilled in the art, may be

made in the form, details of construction and arrangement of the several parts of the garments to which the invention is directed without departing from the inventive concept. Reference is therefore to be had to the appended claims for a definition of the limits of the invention.

This is a continuation in part of application Serial No. 358,035, filed September 23, 1940.

What is claimed is:

1. A garment of the wrap-around type comprising a waist portion including a pair of waist sections, a skirt portion including a pair of sections secured at their upper edges to said pair of waist sections adjacent the waistline and adapted to be wrapped around the body of the wearer in overlapping relation, the overlapping section forming the front of said skirt portion and the underlapping section being of less width than said overlapping section so that its free side edge lies beneath the overlapping section intermediate the side edges of the latter when the garment is worn, means for fastening the garment in wearing position upon the body of the wearer, and means for preventing the free edge of said underlapping skirt section from dropping away from its proper position when the wearer assumes various postures consisting of a piece of material secured to said free edge of the underlapping skirt section at a substantial distance below the waist line and extending upwardly and obliquely away from said free edge and secured adjacent the waist line of the garment to that waist section to which said underlapping skirt section is secured.
2. A garment of the wrap-around type comprising a waist portion including a pair of waist sections, a skirt portion including a pair of sections secured at their upper edges to said pair of waist sections adjacent the waistline and adapted to be wrapped around the body of the wearer in overlapping relation, the overlapping section forming the front of said skirt portion and the underlapping section being of less width than said overlapping section so that its free side edge lies beneath the overlapping section intermediate the side edges of the latter when the garment is worn, means for fastening the garment in wearing position upon the body of the wearer, and means for preventing the free edge of said underlapping skirt section from dropping away from its proper position when the wearer assumes various postures consisting of an adjusting element having its upper edge secured to that waist section to which said underlapping skirt section is secured along a line in prolongation of the upper edge of said underlapping skirt section, and another edge secured to a portion of the free edge of said underlapping skirt section, said element extending from a point on said free edge substantially below the waistline obliquely away from said free edge to said waist portion.
3. A garment of the wrap-around type comprising a waist portion including a pair of waist sections, a skirt portion including a pair of sections secured at their upper edges to said pair of waist sections adjacent the waistline and adapted to be wrapped around the body of the wearer in overlapping relation, the overlapping section forming the front of said skirt portion and the underlapping section being of less width than said overlapping section so that its free side edge lies beneath the overlapping section intermediate the side edges of the latter when the garment is worn, means for fastening the gar-

ment in wearing position upon the body of the wearer, and a tension member connecting at least one point on the free edge of said underlapping skirt section intermediate the length thereof with at least one point adjacent the waistline on that waist section to which said underlapping skirt section is secured but spaced from the points at which said underlapping section is secured thereto, said member extending obliquely between its points of connection to said underlapping skirt section and said waist section.

4. A garment of the wrap-around type comprising a waist portion including a pair of front sections separable down the front of the garment, one of said front waist sections being adapted to overlap at least the bottom portion of the second of said front waist sections when the garment is worn, a skirt portion including a pair of front sections adapted to overlap one another when the garment is worn, the overlapping skirt section being secured at its upper edge to said first front waist section and forming the front of said skirt portion, the underlapping skirt section being secured at its upper edge to said second front waist section but of insufficient width to extend to the free edge of the latter, means associated with said front waist sections for fastening the garment in wearing position upon the body of the wearer, and means for holding the underlapping skirt section in proper position when the garment is worn consisting of an adjusting element secured to that portion of said second front waist section which lies between the free edge of the latter and the free edge of said underlapping skirt section, and also secured to said free edge of the underlapping skirt section at at least one point intermediate the length thereof, said element extending obliquely between said points of connection to said waist section and underlapping skirt section.

5. A garment of the wrap-around type comprising a waist portion including a pair of front sections separable down the front of the garment, one of said front waist sections being adapted to overlap at least the bottom portion of the second of said front waist sections when the garment is worn, a skirt portion including a pair of front sections adapted to overlap one another when the garment is worn, the overlapping skirt section being secured at its upper edge to said first front waist section and forming the front of said skirt portion, the underlapping skirt section being secured at its upper edge to said second front waist section but of less width than said overlapping skirt section so that its free side edge lies beneath the overlapping section inter-

mediate the side edges of the latter when the garment is worn, means including a pair of tie members associated with said front waist sections for fastening the garment in wearing position upon the body of the wearer, and means for holding the underlapping skirt section in proper position when the garment is worn consisting of an adjusting element secured at its upper end to the tie member associated with the underlapping waist section and at its lower end to the free side edge of said underlapping skirt section at a point intermediate the length thereof, said element extending obliquely between its points of connection to said tie member and underlapping skirt section.

6. In a garment of the wrap-around type, a skirt construction comprising a pair of sections for attachment at their upper edges with a waist portion and adapted to be wrapped around the body of the wearer in overlapping relation, the overlapping section forming the front of the skirt, the underlapping section being of less width than said overlapping section so that its free vertical side edge lies beneath the overlapping section intermediate the side edges of the latter when the garment is worn, and an elongated adjusting element secured to the free edge of said underlapping section below its upper edge and having its upper end disposed beyond said free edge for attachment to said waist portion to apply obliquely directed force to said underlapping skirt section and maintain it in its proper position.

7. A skirt construction according to claim 6 wherein the free edge of said underlapping section is substantially straight throughout its length, and the adjusting element consists of a piece of material originally quadrilateral in shape but having two of its adjacent sides secured to said free edge of the underlapping section.

8. A skirt construction according to claim 6 wherein the adjusting element is substantially triangular in shape, having an edge secured to the free edge of the underlapping section.

9. A skirt construction according to claim 6 wherein the adjusting element consists of a strap secured at its lower end to and diverging upwardly away from the free edge of the underlapping section.

10. A skirt construction according to claim 6 and having a belt to which said skirt sections are attached, said belt having free ends and said adjusting element having its upper end secured to that end of the belt which is attached to the underlapping skirt section.

ADA QUINN.
